PAGE MARKING MEANS David V. Wills, 4828 Brown St.,
Philadelphia, Pa. 19139Filed Oct. 20, 1966, Ser. No. 588,681
2 Claims. (Cl. 281—42)

This invention relates, in general, to page marking means for books and the like, and in particular, to a novel permanent marker affixed on individual leaves of a book.

The common book mark is not permanently affixed to a book and therefore is quite susceptible to being lost. It is easily misplaced and often seems to be unavailable when most needed. Book marks have been developed which may be clipped to the leaf of a book or, in the case of the ribbon type, are permanently attached in the binding of the book. Unfortunately, these types of book markers are not entirely satisfactory, since they may be accidentally pulled off a leaf, or from between leaves, to lose the place in the book. Additionally, the permanent binding of a ribbon type book mark is added expense which adds to the final cost of the book.

Of course, it is not recommended to fold a corner of a leaf inward, since this is injurious to the book, yielding an unsightly dog-eared appearance. The novel book mark of the present invention was devised to eliminate all of the above undesired features.

Therefore, to overcome the foregoing and other difficulties of the prior art, the general object of this invention is to provide a novel page marker for a book.

One of the objects of this invention is to provide an improved page marker for a book which is permanently affixed thereto and always available.

Another object of this invention is to provide a permanent type page marker which may be quickly and conveniently utilized.

Another object is to provide a page marker which is permanently affixed to individual leaves of a book and which cannot be easily pulled therefrom, and providing a plurality of marking means.

A further object is to prevent damage and to preserve the appearance of a book by eliminating dog-eared corners and objects which are unevenly received between the leaves thereof.

It is still another object to provide a permanent page marker for a book which is economical to produce by utilizing conventional, currently available materials that lend themselves to standard mass-production manufacturing techniques.

Further and other objects, and a more complete understanding of the invention may be had by referring to the following description and claims, taken in conjunction with the accompanying drawings in which:

FIGURE 1 is a perspective view of a partly open book illustrating individual leaves thereof having one embodiment of the page marker of the present invention,

FIGURE 2 is an enlarged cross-section of the book illustrated in FIGURE 1, in a closed position taken in the direction of arrows 2—2, the page marker being folded inward and out of the way,

FIGURE 3 is a cross-sectional view identical to FIGURE 2, however, illustrating the page marker folded outward to mark a place in the book,

FIGURE 4 is an enlarged cross-sectional view similar to FIGURE 2, of an alternate embodiment,

FIGURE 5 is a cross-sectional view identical to FIGURE 4, however, showing the page marker in an extended position to mark a place in the book,

FIGURE 6 is a perspective view of a book in a slightly open position illustrating several leaves thereof having another embodiment of page marker,

FIGURE 7 is an enlarged cross-sectional view taken along line 7—7 of FIGURE 6,

FIGURE 8 is a perspective view of a slightly open book illustrating individual leaves therein having still another alternate embodiment of the page marker of the present invention, and

FIGURE 9 is a cross-sectional view of FIGURE 8 taken in the direction of the arrows 9—9.

For the purpose of illustrating the invention, there is shown in the drawing the forms which are presently preferred, it being understood, however, that this invention is not limited to the precise arrangements and instrumentalities there shown.

Referring now to the drawings in detail, where like numerals indicate like elements, there are shown in the figures, illustrations of various embodiments of the page marker of the present invention shown on books which are designated generally at 10. The books 10 of a conventional construction having a front cover 12, rear cover 14, a back 15, and leaves 20, 25, upon which the various pages are printed. A conventional binding is employed and may be the economical type binding employing a staple 16, as illustrated at FIGURES 8 and 9.

A tab 30 is permanently affixed at an outside edge 21 of the leaves 20, as illustrated. The tab 30 is foldable along a fold line 35 to fit inward from edge 21 and within the book 10, and alternately, to extend outward beyond the edge for the purposes of marking a place in the book 10.

Now it is desirable that the tabs 30 be received evenly between leaves of the book 10 in order to preserve appearance and not to provide a predilection to open at any particular place, whenever the tabs 30 are folded inward. Thus, a space or indentation 32 is provided for reception of the tabs 30 when folded inward.

It is understood, of course, that it is not necessary to provide a tab member 30 for each individual leaf, it being sufficient to provide a tab 30 for each alternate leaf 20 of a book 10, in the manner shown.

Several alternate embodiments of the invention concept are illustrated in the drawings; however, it is understood that the embodiments there shown are by no means exhausted as to the shape, size, and placement of the tabs 30.

In the embodiment of FIGURES 1, 2 and 3, the tab member 30 is a semi-circular projection of alternate leaves 20 extending outward from the outward edge 21 of each. As illustrated, the adjacent sheets 25 therebetween, each have a contiguous edge 26 with respect to the outside edge 21 of leaves 25, whenever the book is closed. The contiguous edge 26 is of a configuration which corresponds to the tab 30 for an even reception thereof between the leaves of book 10 when the tab is folded inward. In this embodiment, a semi-circular indentation 32 is provided by the configuration. Thus, as shown in FIGURE 2, the tab member 30 may be folded inward on line 35 to fit within indentation 32 and evenly between the leaves 20—35 of the book 10. If it is desired to mark a page, an individual tab member 30 is folded outward, to a position extending beyond the edge 21 to mark the place therein.

The aforesaid embodiment utilized a tab member 30 that was integral with the sheets 20. However, in the book binding art, the outside edges are often not trimmed until after the leaves are assembled together. Therefore, it may be desirable to utilize the embodiment illustrated in FIGURES 4 and 5, wherein the tab member 30 is a separate element in addition to the leaf 20. In this case, the base 37 of each separate tab 30 is secured at the outside edge 21 of leaf 20 by a suitable adhesive with the tab extending inward therefrom as shown. A parallel fold line 35 is made across the tab 30 proximate and parallel to

the base 37. When it is desired to mark a place in a book all that need be done is to fold the tab 30 on the line 35 outward to extend beyond edge 21 as shown in FIGURE 5.

In the embodiment shown in FIGURES 6 and 7, the tab 30 is an impression cut through the leaf 20 leaving the base of the tab integral with the leaf, and in juxtaposition to the outside edge 21, as shown. A fold line 35 may also be provided at the base of each tab 30. In this embodiment of the invention, an integral tab 30 may be provided for each individual leaf, or on alternate leaves, as desired. The tab 30 has a length, measured from the base, which is greater than the distance of the base from the edge 21. In this manner, when the tab 30 is folded outward on line 35 it will extend beyond edge 21 to mark a place in the book 10.

In the embodiment shown in FIGURES 8 and 9, the leaves 25 are alternately arranged so that the outside edge 21, of each of the leaves 20 which is in this instance a folded edge, is positioned proximate the edge 26 of the adjacent leaves. Notice that the tab member 30 is continuous along the entire length of the folded edge 21 which is formed by folding the tab 30 along the fold line 35. Here the contiguous edge 26 of leaf 25 is merely spaced inward from the folded outside edge 21 a sufficient distance allowing the tab member 30 to be folded back upon leaf 25, as illustrated. In this manner, the tab members 30 may be folded inward between the leaves 20-25, for an even reception therein. When it is desired to mark a particular page, the nearest and most appropriate tab member 30 may be folded outward, as illustrated in the FIGURES 8 and 9.

Thus, as a novel and improved page marker for a book has been described above. The present invention may be embodied in other specific forms without departing from the spirit or potential attributes thereof and, accordingly, reference should be made to the appended claims, rather than to the foregoing specification as indicating the scope of the invention.

What is claimed is:

1. A book with page marking means comprising a

plurality of bound imperforate leaves of equal size and uniform thickness each having an outside edge, only alternative first leaves of said book each having a tab, said tab being of reduced dimensions and being foldably secured with and extending only from a portion of the outside edge of its leaf, said tab being foldable to fit inwardly from said edge within said book while overlying a portion on one side of said leaf and alternately unfolded to extend outwardly beyond said edge to mark a page of said book, alternate second leaves of said book each adjacent to a said first leaf and each having a contiguous edge with respect to said outside edge of its said adjacent first leaf, said contiguous edge having a configuration with an indentation corresponding to said tab for an even reception of said tab thereby within leaves of said book when said tab is folded inward, each of said tabs being normally folded inwardly to overlie its leaf and being disposed within the indentation in the edge of the adjacent leaf whereby the tabs do not add to the thickness of the book when foldably disposed within the outside edges of the leaves.

2. The means of claim 1 in which the tabs of said first leaves have a semicircular configuration, and the contiguous edges of said second leaves have a semicircular indentation corresponding to said tabs for said even reception of said tabs thereby within leaves of said book when said tabs are folded inward.
